SUPPORTING STRUCTURE

Filed Sept. 17, 1925

INVENTOR

UNITED STATES PATENT OFFICE

ADOLPH A. THOMAS, OF NEW YORK, N. Y.

SUPPORTING STRUCTURE

Application filed September 17, 1925. Serial No. 56,902.

My invention relates to novel structures for supporting suitable articles or devices in vertical, horizontal or intermediate positions, and permitting easy adjustment of the supported member from one position to the other. As will appear later, my invention is particularly useful for supporting radio loops in vertical or in horizontal receiving position, although the invention is not limited to that field.

Loop antennæ have heretofore been set up in a vertical plane to intercept radiant energy sent out by broadcasting stations. Not only must the loop be placed in vertical position, but for the best results it should point in the direction of the transmitting station. In the broadcasting methods heretofore employed, it has been supposed that the electric oscillations picked up by a loop were travelling in a vertical plane. Hence, it has been necessary to support the receiving loop in vertical position.

It has been proposed to utilize horizontal waves in broadcasting—that is, waves which are propagated in a horizontal plane. In order to receive horizontal waves in a radio set operating on a loop, it is necessary to have the loop in horizontal position. In fact, the same station may send out both kinds of waves at the same time; or, two stations may operate at the same frequency, but one transmitting on horizontal waves and the other on vertical waves. The same loop may be used for receiving either kind of wave, but it must be in vertical position for vertical-wave reception and in horizontal position for picking up horizontal-wave transmission.

It is one of the objects of my invention to meet the foregoing conditions by providing a receiving loop capable of ready adjustment into vertical and horizontal position without dismantling the supporting structure and without the need of tools. For this purpose, I provide a suitable supporting post, or a pair of posts, with a fixed curved rail, or a pair of rails, on which the loop frame is adjustably mounted. This rail may simply be a bent rod extending upwardly from vertical to horizontal, or may be a slotted strip. On this curved rail slides a suitable member con-

nected to the loop frame, and this member is adapted to be clamped on the rail to hold the frame in horizontal or vertical position, or in any position between the two extremes.

If the curved rail is slotted, there is a bolt 55 that operates in the slot and is slidable along the rail between vertical and horizontal positions. To the outer end of the bolt is connected the loop frame, and a wing nut or like member 60 clamps the frame in adjusted position against the rail. The bolt may be hinged at one end to the support, or it may be a short piece held on the rail by a nut at its outer end. If the supporting rail is simply 65 a rod or solid strip, the connecting member on the frame is recessed to fit over the rod with a sliding contact. A set screw or the like 70 clamps the recessed member in adjusted position on the supporting rod.

Several illustrative embodiments of my invention are shown in the accompanying drawings, in which

Fig. 1 shows in perspective a loop-supporting device constructed in accordance with my invention, the loop (partly broken away for lack of space) being shown supported in vertical receiving position;

Fig. 2 is a side view (on a smaller scale) of the construction shown in Fig. 1, with the loop supported in horizontal receiving position;

Fig. 3 shows in cross-section, on line 3—3 of Fig. 4, an enlarged side view of the connection between the support and the loop frame, the latter being shown in horizontal position by full lines and in vertical position by dotted lines;

Fig. 4 is an end view of Fig. 3, partly in section;

Fig. 5 is a view similar to Fig. 3, showing a 90 modified form in which the supporting rail is a solid rod or strip (that is, without a slot);

Fig. 6 is an end view of Fig. 5;

Fig. 7 shows in cross-section, on line 7—7 of Fig. 8, a further modification including a 95 pivoted bolt mounted on the support; and

Fig. 8 is an end view of Fig. 7, partly in section.

Referring first to the construction illustrated in Figs. 1—4, there is a base 1 which sup- 100

ports a post or stand 2. The parts 1 and 2 are to be considered as representing any practical support for the loop frame, but for convenience I shall refer to the member 2 as a post, 5 without thereby intending any limitation. The post 2 may be pivotally mounted on base 1, as by a pin 3 or otherwise, for the purpose of permitting horizontal adjustment of the vertical loop. On the top of post 2 is fixed a 10 plate 4, which is provided with a curved rail 5 having a longitudinal slot 6. The rail 5 is preferably formed integral with plate 4.

A loop support indicated as a whole by L is provided with a cross-arm 7. In the present instance, this arm consists of two sections secured to a central metal bracket 8, as best shown in Fig. 4. This bracket is recessed as indicated at 9, and the ends of the sections of the cross-arm preferably abut 20 against the shoulders 10 formed on the bracket 8, so as to provide a rigid connection between the bracket and the two sections of the cross-arm. Through a hole in the bracket 8 extends a bolt 11 provided with a 25 head 12 at one end and a wing-nut 13 at the other end. The bolt 11 projects through the slot 6 on rail 5 and is thereby slidably mounted on the rail.

As may be seen from Fig. 3, the loop frame L is mounted in vertical and horizontal receiving position on the support 2 by simply sliding the bolt 11 along the rail 5 and then clamping the loop frame in adjusted position by means of the wing-nut 13. Fig. 3 shows the loop frame supported in horizontal position, the vertical position of the frame being indicated by means of dotted lines. By accommodating the wing-nut 13 in the recess 9 of bracket 8, only a 40 very short bolt is required. Also, this arrangement of the nut contributes to the neat appearance of the supporting structure as a whole.

In Figs. 5 and 6 the supporting rail is in the form of a solid strip or bar 14 formed integral with, or attached to, a plate 15 on post 2. To the cross-arm 7 of the loop frame is secured a connecting piece 16 which is shown in the form of a hollow rectangular bracket adapted to fit slidably over the rail 14. A set screw 17 clamps the loop frame in adjusted position on the rail 14. Fig. 5 shows the horizontal position of the loop in full lines and the vertical position in dotted lines.

The modification of Figs. 7 and 8 differs from the construction shown in Figs. 3 and 4 in having a bolt 18 pivoted at 19 on the plate 4 which carries the slotted rail 5. The pivoted bolt 18 operates in exactly the same way as the bolt 11 of Figs. 3 and 4 for supporting the loop frame in vertical and horizontal receiving position. Therefore, what 63 has been said about Figs. 3 and 4, applies

fully to Figs. 7 and 8, without the necessity of repetition.

It will be seen from the foregoing that I have provided very simple means for supporting a loop in vertical as well as horizontal receiving position. No tools or separate securing means are necessary in holding the loop rigidly in either receiving position. All that the operator needs to do is loosen and tighten a finger nut or a set-screw.

The loop frame L may be of any practical construction and design, and I have shown a rectangular loop frame merely for convenience. The cross-arm 7 in Figs. 3-10 is intended to represent, in a fragmentary way, any suitable loop frame. The particular point or points of connection between the loop frame and the support will depend largely upon the form and size of the frame on which the loop wires are wound. In the drawings I have shown the loop frame connected at one point only on a cross-arm. If it is desired to connect the loop frame at the sides to the support, there would be a pair of supporting posts and the connections previously described would be duplicated at the sides of the loop frame. This will be understood without further description or illustration.

Since the loop frame in vertical position hangs at one side of the supporting post 2, the base 1 may be extended forwardly so that the center of gravity of the loop frame may fall well within the body of the base to secure stability of the structure as a whole.

It will not be necessary to show or describe any circuit connections for the loop, because these are well understood and they form no part of my invention. The base 1 may be provided with a pair of binding posts 24, to which the ends of the loop are connected.

It goes without saying that the drawings herein described in detail are not shop drawings, and the proportions of the various parts in the enlarged views have been purposely exaggerated in order to make the drawings as clear as possible.

Although the supporting rail in the various modifications is shown in the form of a circular arc, it is obvious that this precise configuration is not necessary. It is sufficient if the rail is so bent or curved that the frame may be supported in vertical and in horizontal position.

The particular constructions herein shown and described are to be considered merely as illustrative examples of my invention and not as limitations or restrictions. Changes and further modifications will doubtless occur to those skilled in the art without departing from the scope of the invention as defined in the appended claims.

It is hardly necessary to explain that the descriptive terms "vertical" and "horizontal" in reference to the position of the supported

frame are not used here in their strict mathematical or physical meaning. In ordinary usage, those words generally indicate positions that merely approximate true vertical and true horizontal. Furthermore, radio receiving loops need not necessarily be in the exact vertical or horizontal position in order to perform their intended functions, and it is in this broad and practical sense that the words "vertical" and "horizontal" are used in the description and the claims. When I speak of a frame in the claims, I use the word in its broadest possible sense to include any suitable member supported in adjustable position, such as a loop frame, picture frame, mirror and numerous other articles.

What I claim as my invention is:

1. A structure comprising a support, a plate secured on said support, a curved slotted rail formed integral with said plate and extending upwardly therefrom, a bolt hinged on said plate and projecting through the slot in said rail, said projecting end of the bolt being adjustable in said slot, a frame connected to the projecting end of said bolt, so that said frame may be adjusted on said rail to any position between the ends of said slot, and a nut on the outer end of said bolt for clamping said frame against said rail in adjusted position.

2. As a new article of manufacture for use in supporting structures, a flat plate provided with an integral flat rail which extends from one edge of the plate and curves over the same, the flat surface of said rail lying in a curved plane which is substantially a continuation of the plane of said plate, the edges of said curved rail being disconnected from said plate.

3. As a new article of manufacture for use in supporting structures, a plate provided with a curved slotted rail, a bolt hinged on said plate and projecting through the slot of said rail, a manually adjustable member on the projecting end of said bolt, and a part connected to said bolt and arranged between said rail and member, whereby said member is adjustable to clamp said part to the rail in any position of the bolt.

4. As a new article of manufacture for use in supporting structures, a plate provided with an integral slotted rail which extends from one edge of the plate and curves over the same, a bolt hinged on said plate and projecting through the slot of said rail, and a clamping nut on the projecting end of said bolt.

5. In a supporting structure, a frame provided with a cross arm consisting of two separate sections and a middle connecting piece, said connecting piece being formed of a metal strip having a pair of end projections and a central off-set portion, the sections of said cross arm being secured to the ends of said connecting piece and abutting against

the sides of said central offset portion, and a support for holding said frame in any position between horizontal and vertical, said support including a bolt projecting through a hole in said off-set portion.

6. In a supporting structure, a frame provided with a cross arm consisting of two separate sections and a middle connecting piece, said connecting piece being formed of a metal strip having a pair of end projections and a central off-set portion arranged to form a recess, the sections of said cross arm being secured to the ends of said connecting piece and abutting against the sides of said central off-set portion, a support for holding said frame in any position between horizontal and vertical, said support including a bolt projecting through a hole in said off-set portion, and a nut on the bolt in said recess.

7. A supporting structure comprising a base, a curved slotted rail extending rigidly and flatwise from said base, an adjustable member pivoted at one end to said base and at its free end projecting radially through the slot in said rail, and means for releasably connecting the free end of said member to said rail in any adjusted position of said member, said connecting means being adjustably mounted on the projecting end of said member.

8. A structure comprising a support, a curved slotted rail fixed on said support, a bolt hinged at one end and at its free end projecting through the slot in said rail, said projecting end of the bolt being radially adjustable along said slot, a member connected to the adjustable end of said bolt, and means engaging said adjustable end of the bolt to secure said member to said rail in any adjusted position.
